UNITED STATES PATENT OFFICE

166,135

ARTIFICIAL CHRISTMAS TREE

Ludwig Stark, Springfield, N. J.

Application September 12, 1951, Serial No. 16,613

Term of patent 7 years

(Cl. D29—1)

To all whom it may concern:

Be it known that I, Ludwig Stark, a citizen of the United States, residing in Springfield, Union County, New Jersey, have invented a new, original, and ornamental Design for an Artificial Christmas Tree, of which the following is a specification, reference being had to the accompanying drawing, forming a part hereof.

Fig. 1 is a perspective view of an artificial Christmas tree, showing my new design; and Fig. 2 is a side elevational view thereof.

I claim:

The ornamental design for an artificial Christmas tree, as shown.

LUDWIG STARK.
